ADJUSTABLE SPRAYING DEVICE

Jerry Tyler, Niles, Mich.

Application May 22, 1933, Serial No. 672,158

5 Claims. (Cl. 299—58)

This invention relates generally to a humidifying and cooling apparatus and more particularly to a nozzle and baffle construction.

One of the main advantages of my construction resides in the several adjustments embodied therein whereby the relationships between the baffle plate and the jet of water and the baffle plate and the produce or the like which is to be cooled may be altered so that an optimum of 10 conditions prevail.

Briefly described, the above advantages are attained by mounting the impact of the baffle plate so as to be vertically adjustable and also utilizing the same construction for tilting the plate in either direction. Also, the cylindrical dome supporting the baffle plate is mounted for revoluble movement whereby the desired direction of the spray or vapor which issues from the baffle plate may be properly directed.

Another advantage resides in the detachable mounting of the baffle plate which permits the insertion of one's fingers into the top part of the cylindrical shell whereby cleaning or adjustment of my novel orifice member may be easily attained. Also, it is to be noted that the positioning of this orifice element is such that any leakage of water therearound is taken care of, the same trickling downwardly through the overflow pipe.

A feature of importance is the vertical adjustment of the baffle both with respect to the jet nozzle and the open end of the spray shield whereby the amount or volume of mist emitted may be nicely controlled. The baffle plate may be elevated above the opening of the spray shield to permit full volume of mist emission or may be lowered toward the end of the said shield to partially or completely close the same thereby governing the amount of mist delivered from 40 maximum to nothing.

Other objects will become apparent during the description of the device shown in the accompanying drawing in which,

Fig. 1 shows a side view of several of my devices, 45 two of these being in operation and the other one being closed.

Fig. 2 is a sectional view taken through the upper portion of my novel construction.

Fig. 3 is a fragmentary side view showing the 50 baffle plate horizontally positioned.

Fig. 4 is a sectional view illustrating an angular adjustment of the baffle plate.

Fig. 5 is a sectional view showing the baffle 55 plate in closed position, and

Fig. 6 is a sectional view taken along the line 6—6 of Fig. 2.

Like numbers refer to like parts in the several views.

Referring to Fig. 1, numeral 10 indicates a 5 water pipe supplying water under pressure and risers 11 extend upwardly therefrom. Each of these risers 11, see Fig. 2, is connected to a sleeve member 12 by means of the threaded connection 13. The sleeve member 12 has a tapered conical 10 outer surface as indicated at 14 and a central cylindrical surface as indicated at 15, and terminates in a threaded upper portion 16, the diameter of this upper threaded portion being less than the diameter of the smooth central cylindrical 15 portion and, in turn, the diameter of the cylindrical portion 15 is less than the diameter of the threaded portion therebelow.

An orifice member 20 has a small cylindrical 20 upper projection 21 and is provided with a finger gripping surface 22 whereby the same may be readily connected to or disconnected from the threads 16 in the sleeve member 12. The orifice member 20 is provided with a cylindrical recess 23 and a small orifice 24 extends upwardly therefrom and through the cylindrical portion 21, this providing a passageway for water as will be readily understood. A screen member 25, shaped as shown, prevents foreign particles from clogging the orifice 24, such being frictionally inserted into 30 the recess 23.

A cylindrical dome member 30 has an overflow pipe 31 threaded attached thereto as indicated at 32 and integrally formed vanes 33, see Figs. 2 and 6, extend inwardly and form a ring-like member 34, the inner surface of such being tapered at 35 and receiving the conical tapered surface 14 previously referred to. Thus the cylindrical dome member 30 may be rotatably adjusted with respect to the riser pipe 25. The smallest diameter 40 of the ring member 34, however, is of sufficient size to permit the dome member 30 to be lifted vertically over the finger gripping portion 22 of the orifice member 20. Thus the dome member 30 and its overflow pipe 31 may be removed whenever desired.

The dome member 30 has ears 36 extending upwardly therefrom at diametrically opposite points, these ears being slotted as indicated at 37.

A baffle plate 40 has a thickened portion 41 near its central portion, this thickened portion being bored and threaded at either end to receive the adjusting screws 50, see Fig. 2. It will be noted that the slots 37 terminate slightly above 55

the upper edge of the dome member 30 whereby the same will be completely closed, see Fig. 5, whenever the studs 50 are loosened and gravity causes the baffle plate to assume the position shown. However, it is to be understood that in case my spraying device is used at an angle to the vertical that the baffle plate 40 can be clamped in its closed position or any other position as desired.

10 *The operation*

As shown in Figs. 1, 3 and 4, the baffle plate 40 is located at the extreme top of the slots 37 but in practice the studs 50 are loosened and the baffle plate 40 is adjusted to the desired height above the dome member 30 and at the same time the angularity of the same with respect to the horizontal is determined and the tightening of the means 50 maintains the baffle in its chosen position. Also, the dome member 30 may be manually rotated, the ring 34 turning upon the sleeve element 12, and thus the direction of the vapor regulated. The unvaporized drops of water, see Fig. 4, gravitate downwardly through the dome member 30 and then into the waste pipe 31.

29 When the impact plate is flat, as shown in Fig. 3, the spray floats out all sides thereof while when the same is tipped, see Fig. 4, the volume of the mist on the back side is decreased in proportion to the slope thereof, and the volume of the open side is increased in quantity and coverage. Due to the impact plate being on a slope, the mist shooting out of the open side rises higher in the air and gives greater coverage. Therefore, 30 by raising or lowering the impact plate, and utilizing the set screw adjustment, the amount of mist developed whether the impact plate is flat or on a slant can be graduated.

40 By lowering the impact plate very close to the cylinder, and leaving only a very small opening, it is possible to cut down the spray, except for a very little amount of extremely fine mist which is a great advantage at certain times and on certain vegetables, to keep them from getting too wet.

45 Whenever desired, the set screws 50 may be removed and the orifice element adjusted or removed by the finger gripping means 22, the screen 25 being removed and cleaned, if desired, and due 50 to my particular construction, this is possible without elevating the dome 30 and its waste pipe 31 from its normal position.

Having thus revealed this invention, I claim as new and desire to secure the following combinations and elements, or equivalents thereof, by Letters Patent of the United States.

I claim:

1. A spray device comprising, a nozzle constructed to deliver a stream of water, a drainage member surrounding the nozzle and having an upward opening and an impact member having a flat impact surface located in the path of said stream and over the said opening of the drainage member, said impact member being mounted for adjustment both in a direction in alignment with said stream and as to angularity of its impact surface relative to said stream, said axis about which the tilting occurs being crossed by the prolongation of the path of the stream. 5 10

2. In a spraying construction of the class described, a cylindrical member having an open upper end, means for forcing a small jet of water upwardly through the member in spaced relationship to its inner surface, baffle plate means, and means for adjustably mounting said baffle plate whereby it may be moved to completely close the open upper end of said cylindrical member. 15 20

3. A spraying device including a nozzle constructed to eject a stream of water, an impact member having an impact surface and a single means for mounting said impact member with its impact surface in the path of said stream for adjustment both in a direction parallel with said stream and as to a plurality of different angularities of said impact surface relative to the axis of said stream. 25 30

4. A spray device comprising, a nozzle constructed to deliver a stream of water, a drainage member partially surrounding said stream and an impact plate having an impact surface located outside of said drainage member and in the path of said stream and means for adjustably mounting said impact member for movement in alignment with said stream, and also for adjusting the angularity of said impact surface to a number of positions relative to said streams, said adjustable mounting means including parallel slotted ears extending upwardly from said drainage member, and fastening means extending laterally from said impact plate through the said slots. 40

5. In combination, a sleeve member adapted to 45 receive water under pressure therein, a dome member revolubly mounted upon said sleeve member and extending upwardly therefrom, a baffle plate tiltably and axially slidably mounted upon said dome member near its upper end, an orifice 50 element mounted in said sleeve member, said orifice element directing the water towards the baffle plate and means for locking the baffle in the chosen one of its several positions.

JERRY TYLER. 55
